US0D1094107S

(12) **United States Design Patent** (10) **Patent No.:** **US D1,094,107 S**
(45) **Date of Patent:** **** Sep. 23, 2025**

(54) **BOTTLE**

(71) Applicant: **Guangdong Woodsun Housewares Co., Ltd**, Yangjiang (CN)

(72) Inventor: **Sihua Huang**, Yangjiang (CN)

(**) Term: **15 Years**

(21) Appl. No.: **29/927,026**

(22) Filed: **Feb. 2, 2024**

(51) LOC (15) Cl. **07-01**

(52) U.S. Cl.

USPC **D7/511**; D7/510; D7/536

(58) **Field of Classification Search**

USPC D9/531, 536, 434, 435, 436, 440, 443,
